UNITED STATES PATENT OFFICE.

DAVID ROSENBERG AND JOHN B. HARTNETT, OF PROVIDENCE,
RHODE ISLAND.

WINDOW-SHADE FIXTURE.

No. 856,302.

Specification of Letters Patent.

Patented June 11, 1907.

Application filed July 30, 1906. Serial No. 328,345.

To all whom it may concern:

Be it known that we, DAVID ROSENBERG and JOHN B. HARTNETT, citizens of the United States, residing at the city of Providence, in the county of Providence and State of Rhode Island, have invented certain new and useful Improvements in Window-Shade Fixtures, of which the following is a specification, reference being had therein to the accompanying drawing.

This invention relates to improvements in combination shade and window curtain supports and has for its object to provide a simple and inexpensive bracket or support of this character that can be quickly and rigidly applied to a window casing without the use of screws or nails extending into the casing through the front face of the same.

A further object of the invention is that the device may be used as a combination shade roller, bracket, and curtain pole support, or the curtain pole holder may be removed and the bracket used for a shade roller alone, if desired.

In other devices of this character where spurs alone have been used for fastening the support to the window casing, it is found that the support works loose by the frequent working of the shade up and down and after a time gives way and falls. My improved device is provided with a pair of projecting lips or spurs which are forced into the face of the window frame. The device is also provided with a flange which projects rearwardly over the top of the window casing through which flange is threaded a binding screw preferably pointed on its end. The point of this screw is set or forced tightly onto the wood on the top of the casing thus serving to draw up and tightly bind or grip the projecting spurs in the wood to hold the bracket rigidly in place and positively prevent the same from being loosened or withdrawn therefrom.

Another feature of the invention is that the curtain pole holder is made separate and independent from the shade curtain bracket and is provided with means whereby it may be readily secured to said shade bracket by a screw and further supported in its position by a hooked portion that is adapted to engage the upper edge of said bracket to hold said support rigidly in the proper position.

The invention is fully set forth in this speci-

fication and more particularly pointed out in the appended claims.

In the accompanying drawings: Figure 1—is a side elevation showing a portion of the window frame in cross section and the shade holder in position on said window frame, and the curtain pole holder in position on said shade holder bracket. Fig. 2—is a perspective view showing the rear face of the shade curtain bracket when the curtain pole holder is removed therefrom, also showing the inwardly projecting spurs which are preferably formed from the stock of the bracket. Fig. 3—is a detail perspective view of the curtain pole holder showing the lip or hooked portion that is adapted to engage the upper edge of the shade curtain bracket to assist its screw in supporting the holder in a horizontal position. Fig. 4—is a detail of the tightening or binding screw that is threaded through the rearwardly projecting flange of the shade curtain bracket to engage the upper edge of the window frame and bind and hold the bracket rigidly in position. Fig. 5—is a view showing the shade roller bracket as it appears when blanked from sheet metal.

Referring to the drawings at 1 is a portion of the window casing to which a shade roller bracket 2 is adapted to be attached on either side of the window. This bracket is preferably made of sheet metal being first blanked out in the form illustrated in Fig. 5, and is provided with two inwardly projecting spurs 3 and 4 which are preferably punched or formed from the stock itself in the manner illustrated in Figs. 2 and 5, and are adapted to be forced or pressed into the wooden window casing. An extending portion 5, adapted to receive the end of the shade roller is turned outward to project from the face of the bracket and is provided with a suitable slot or hole 6 to receive the ends of the roller. The upper portion of the bracket 7 is turned back at right angles to the body to form a flange for the purpose of engaging the top of the window casing, as shown in Fig. 1. This flange is provided with a threaded hole 8 for the reception of the binding screw 9. The lower end of the bracket is provided with a downwardly extending leg 10 which serves as a bearing to better support the bracket when under excessive strain.

Another feature of this invention is the removable curtain pole holder 11 which is pro-

- vided at its outer end with a semi-circular or hook-shaped portion 12 adapted to receive a suitable pole for holding lace curtains or other suitable window draperies. The inner end 5 17 of this holder is adapted to set closely against the face of the bracket and is provided with a hole 13 through which a screw 18 is inserted into the threaded hole 14 in said bracket. The holder is further supported by 10 means of the hooked portion 15 that is adapted to engage the upper edge of the bracket to further and more rigidly support said holder to said bracket. The outwardly extending shank portion 16 is adapted to pass beneath 15 the opening 6 in the bracket so as not to interfere with the free placing or removing of said shade roller while said holder is fixed thereto.
- An essential feature of this device is the means by which the bracket is rigidly secured 20 to the window frame, by first inserting the spurs into the face of the casing and then setting up the binding screw, causing the point to embed itself into the casing and at the same time to draw upward on the bracket and 25 cause the spurs to bite the wood and tightly bind and grip the same to hold the bracket rigidly in position.

Another feature of the invention is the means by which the curtain pole holder is 30 connected to said bracket which is that of its end setting squarely against the face of the bracket and being supported by a hooked portion integral with said holder for further supporting the binding screw which is passed 35 through the holder and threaded into the bracket. By this construction the holder may be readily removed from the bracket by simply taking out the screw 18 leaving only a small hole in the side of the bracket which 40 bracket may then be used for a shade holder alone, if desired.

Having thus described my invention, what I claim as new and desire to secure by Letters Patent, is:

- 45 1. A shade roller bracket struck up from

sheet metal, inwardly extending integral spurs adapted to be driven into the casing, a rearwardly extending integral flange on the upper edge of said bracket, a screw threaded through said flange and provided with a pointed end whereby the same may be caused to engage the top of the casing and exert an upward gripping tension on said spurs to hold the bracket firmly in the casing. 50

2. A combination window shade and drapery support, comprising a shade roller bracket struck up from sheet metal, inwardly extending integral spurs adapted to be driven into the casing, a rearwardly extending integral flange on the upper edge of said bracket, 55 a screw threaded through said flange and provided with a pointed end whereby the same may be caused to engage the top of the casing and exert an upward gripping tension on said spurs to hold the bracket firmly in the casing, 60 and a drapery support detachably connected to said bracket.

3. A combination window shade and drapery support, comprising a shade roller bracket struck up from sheet metal, spurs 70 extending inward from the body of the bracket and adapted to be driven into the casing, a flange on the upper edge of said bracket, adapted to extend over the upper edges of the casing, a screw threaded through 75 said flange whereby a tension is exerted on said spurs causing them to grip or bind in the wood to firmly retain the bracket in position, a drapery pole support, the inner end of said support being adapted to rest against the 80 face of said bracket, a lip on said support adapted to engage said bracket and a screw to further secure said support to said bracket.

In testimony whereof I affix my signature in presence of two witnesses.

DAVID ROSENBERG.
JOHN B. HARTNETT.
